UNITED STATES PATENT OFFICE

FREDERICK W. BARRETT, OF SPRINGFIELD, OHIO, ASSIGNOR TO THE
BARRETT PUBLISHING COMPANY, OF SAME PLACE.

TALLY-SHEET.

SPECIFICATION forming part of Letters Patent No. 505,304, dated September 19, 1893.

Application filed October 20, 1892. Serial No. 449,424. (No specimens.)

To all whom it may concern:

Be it known that I, FREDERICK W. BARRETT, a citizen of the United States, residing at Springfield, in the county of Clark and State 5 of Ohio, have invented certain new and useful Improvements in Tally-Sheets, of which the following is a specification, reference being had therein to the accompanying drawings.

My invention relates to certain new and 10 useful improvements in tally sheets.

The object of my improvements is to provide means for tallying, in the smallest convenient space, a large number of candidates as well as those belonging to a large number 15 of parties, and for tallying the votes cast for such candidates, by straight ballots and by scratched ballots, and also those cast for scattering candidates, the peculiarities of arrangement and the advantages of said improvements, being fully and particularly described 20 hereinafter and claimed.

In the accompanying drawings on which like reference letters indicate corresponding parts: Figure 1, represents one side of a tally 25 sheet suitably ruled and printed to illustrate my improvements; Fig. 2, another side of the same or a different sheet for further illustration; and Fig. 3, a book form of said tally sheet.

30 The letter A designates a sheet or sheets for tallying, suitably ruled at one portion B, for tallying the straight ballots for the respective parties in an election. In another adjacent portion C, preferably on the same 35 sheet and on the same page, space is allotted for tallying scratched ballots of the regular party candidates. In another portion D, Fig. 2, the votes for the scattering candidates are tallied. In the portion designated by B for 40 tallying the straight ballots, the tally squares are arranged opposite the respective party names in the column at the left, and the straight votes marked in said tally spaces in the usual manner; the total votes by straight 45 ballots being marked in the column at the right, designated "Votes on straight ballots." In the portion designated C, Fig. 1, the tally spaces are divided by columns for the regular party tickets respectively, or as in the 50 illustration, Fig. 1, Republican, Democratic, Prohibition and People's party. At the left

of this portion or division is a column designated "Offices to fill," in which the title of the office is marked, such column serving for all the four parties adjacent thereto. For instance, the office of governor has a Republican candidate, "Richard Roe," and a Democratic candidate therefor, "John Doe." The straight ballots for the Republican candidates are marked in the portion B, but any scratched 60 ballots are each marked in the portion or division C, according to the respective candidates voted for. Thus if a Republican candidate for governor received three hundred straight ballots, as shown in division 65 B, and fifty votes be scratched ballots, as shown in the division C, his total vote will be marked opposite his name in the column E, namely, three hundred and fifty, thus showing, at a glance, his total vote. Similarly the 70 straight ballots for a Democratic candidate, namely, two hundred, as shown in division B, will be added to the votes received on scratched ballots, namely, forty in division C, making the total for the Democratic candidate 75 for governor "John Doe," to show two hundred and forty opposite his name in the column E'; the other regular party candidates will be tallied in the same way, and the candidates for the successive offices on the tickets will 80 be likewise tallied in the division C, Fig. 1. Each candidate's vote will thus be shown at a glance. In nearly every election, however, there are more or less names belonging to no particular party and not regularly named and 85 each must be tallied; for this purpose I provide a portion or division D of the tally sheets designated "Scattering candidates." This portion has similar tally spaces and columns for the candidates' names, together with a 90 column, "Offices to fill," common to all such spaces. For instance, "Paul Jones" receives thirty votes, and not being one of the regular party candidates is tallied in the division D, as shown in Fig. 2, opposite the office he is 95 voted for, and his total votes marked opposite his name in the column e. At the bottom of this division D, or any other convenient place, is located the certificate F of the judges and clerks of the election, as shown by Fig. 2. At 100 one end of the sheet is the space for the place and date of election as shown at G, Fig. 1.

The remainder of the page allotted to scattering candidates affords a place H, whereon may be printed the title of the tally sheet or any directions, or other matter, suitable for the instruction or information of the users of the same. The sheet may be folded in any convenient manner for filing, the spaces allotted to the respective party candidates in the division C, Fig. 1, indicating a convenient line of folding, as at a, in said figure. Thus it will be seen that the straight ballots are tallied horizontally at the top and substantially the whole length of the sheet, and the total per party marked at the right, as indicated; also that the scratched ballots for each party are allotted to a separate adjacent portion of the sheet, where each individual candidate's total vote is marked opposite his name, such total footing being the sum of the votes by straight ballots and those by scratched ballots; furthermore that the irregular or scattering candidates are allotted a separate division or portion of the tally sheet, adjacent or opposite the regular candidates, whereby the tallying of such scattering votes may be correctly recorded without liability to confusion with the regular candidates, and yet convenient thereto, as on the same sheet; and finally that the whole number of candidates and the ballots therefor, of whatever party or character of vote, is certified to as hereinbefore described and illustrated.

Referring to Fig. 3, I have shown a still more condensed arrangement, the tally sheet being in book form. The portion devoted to straight ballots is arranged across the top of the main sheet, and a part of the division for scratched ballots is arranged below, on the main sheet, as in Fig. 1, but only spacements for two parties are provided on the main sheet for use in connection with the column headed "Offices to fill;" while the additional spacements for the remaining parties are upon an auxiliary sheet A' stitched or otherwise secured, as shown in Fig. 3, so as to be used with the same column headed "Offices to fill," on the main sheet. Thus if the number of parties is large, one or more of these auxiliary sheets A' can be applied to the main sheet and used therewith. The certificate F, in the form shown in Fig. 3, is conveniently placed at the right of the main sheet, and balances the "Offices to fill" at the left, so that the main sheet may be folded at a conveniently. The term "tally sheet" is used to designate one or more sheets used for tallying purposes, whether it be in a single sheet, as in Fig. 1, or in a condensed form with main and auxiliary sheets, as in Fig. 3.

Having thus fully described my invention, what I claim as new, and desire to secure by Letters Patent, is—

1. A tally sheet, having a portion or division B of the sheet devoted to straight ballots, consisting of tally spaces, a total column and a column for the names of the parties; a portion C devoted to scratched ballots, consist-

ing of spacements or divisions in succession across the sheet each spacement or division devoted to a single party, and consisting of 70 a candidate column, tallying spaces, a total column for said spaces and a column for the sum of the straight and scratched ballots for each candidate, and a common column devoted to the offices on the tickets of the respective 75 parties.

2. A tallying sheet, having a division or portion for tallying the straight ballots of the respective parties arranged across the head of the sheet; a series of spacements having candidate columns, tally spaces and total columns for the respective parties, and a common column for designating offices for all of said parties, arranged below said head portion, and devoted to scratched ballots, where 80 by the straight ballots are tallied in the first division or portion, B and the scratched ballots in the second portion C of the tally sheet opposite their respective party candidates, and the total for each candidate's name, is 85 also shown opposite thereto.

3. A tally sheet, having a portion B of the sheet devoted to straight ballots of the respective parties, and consisting of tallying spaces, a total column, and a party column; 95 and a space C devoted to scratched ballots, and consisting of a set of candidate columns, tallying spaces, total columns for said spaces, and total columns for the sum of the straight and scratched ballots counted for each design- 100 nated candidate, all substantially as shown and described.

4. A tally sheet having a division B for tallying straight ballots of the regular parties, and a division or portion C for tallying the 105 scratched ballots of the said parties' candidates separately; a portion or division D on the reverse side of the sheet devoted to scattering candidates consisting of a column for the candidates' names, tally spaces therefor, 110 total columns, and a common column for the offices voted for; and a portion F devoted to the certificate of said sheet, all substantially as shown and described.

5. In a tally sheet, the combination with a 115 main sheet having a portion B devoted to tallying straight ballots arranged across the head of the sheet, and a portion C for tallying scratched ballots consisting of spacements ruled for tallying, and of columns for the candidates, and a column devoted to the names of the offices to be filled, of an auxiliary sheet A' ruled to form tallying and candidate columns, and constituting the remainder of the portion or division of the tally sheet devoted 120 to scratched ballots, and secured to the main sheet opposite the common office column, substantially as shown and described.

In testimony whereof I affix my signature in presence of two witnesses.

FREDERICK W. BARRETT.
